Watson E. Coleman

Attorney

UNITED STATES PATENT OFFICE.

SAMUEL J. RAWLINGS, OF KEARNY, NEW JERSEY.

DOOR HOLDER.

Application filed July 22, 1924. Serial No. 727,542.

To all whom it may concern:

Be it known that I, SAMUEL J. RAWLINGS, a citizen of the United States, residing at Kearny, in the county of Hudson and State 5 of New Jersey, have invented certain new and useful Improvements in Door Holders, of which the following is a specification, reference being had to the accompanying drawings.

10 This invention relates to certain improvements in door holders and it is an object of the invention to provide a device of this general character embodying novel and improved means whereby the door may be held ajar, said means being releasable to permit the door to be swung into open position for entrance or exit only when the door is in completely closed position.

Another object of the invention is to provide a novel and improved holder of this 20 general character whereby a door may be effectively held ajar and in a manner whereby said means cannot be rendered inoperative to permit full opening of the door by 25 a person outside of the room in which the door opens.

An additional object of the invention is to provide a novel and improved device of this kind comprising means whereby a door 30 may be effectively held ajar and which is also adapted to be used as a check to hold the door in fully open position.

The invention consists in the details of construction and in the combination and arrangement of the several parts of my improved door holder whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

50 Figure 1 is a fragmentary elevational view illustrating a holder constructed in accordance with an embodiment of my invention and in applied position, a second arrangement of the holder being indicated by broken lines;

Figure 2 is a sectional view taken substantially on the line 2—2 of Figure 1, illustrating my improved holder in top plan the associated door being indicated ajar and in fully open position by broken lines; 55

Figure 3 is an enlarged fragmentary view partly in section and partly in elevation 60 illustrating in detail my improved holder the door being in fully closed position;

Figure 4 is a view partly in section and partly in top plan of the device as illustrated in Figure 3; 65

Figure 5 is a fragmentary view in top plan of my improved holder as herein disclosed with the rod in position to hold the door ajar;

Figure 6 is a sectional view taken substantially on the line 6—6 of Figure 5; 70

Figure 7 is a sectional view taken substantially on the line 7—7 of Figure 5.

My improved holder is particularly adapted for use in connection with doors 75 of staterooms and is known on shipboard as an ajar hook for holding the doors partly open for ventilation. However, I do not wish to be understood as limiting myself to this particular use as the same can be used 80 with equal facility in hotels and private homes.

As disclosed in the accompanying drawings, W denotes a wall provided with a door opening O with which coacts in a well-known manner a swinging door D opening 80 within the room.

Secured by the screws 1 or the like to the inner face of the door at a desired point along its free vertical marginal portion is 85 a plate 2, said plate immediately adjacent to the free vertical edge of the door being outwardly disposed, as at 3, on a predetermined incline and terminating in the vertically spaced knuckles 4 preferably three in 90 number. Snugly fitting between the lower two knuckles 4 is a plate 5 while interposed between the upper two knuckles 4 is a washer 6. Disposed through the knuckles 4, the washer 6 and the plate 5 is a bolt 7 95 having associated therewith a holding nut 8, said bolt 7 serving as a pintle about which the plate 5 has swinging movement.

The plate 5 is provided with a circular extension 9 the axis of which being perpendicular to the axis of the plate 5. This ex- 100

tension 9 is partially received within a recess 10 provided in the lower portion of the inner extremity of a rod 11 of predetermined length. The inner extremity of the rod 11 is enlarged, as at 12, the major part of said enlarged portion being disposed above the rod and having an opening 14 extending lengthwise therethrough, the outer end 15 of which being slightly reduced while the inner end of the opening is closed by the plug 16 threaded within said end portion of the opening 14. Slidably disposed through the restricted end 15 of the opening is a plunger 17 the inner end of which being enlarged, as at 18, to prevent the plunger passing entirely through the restricted end 15 of the opening. The plunger 17 is properly applied upon removal of the plug 16. The plunger 17 is constantly urged outwardly by an expansible member 19, herein disclosed as a coil spring, arranged within the opening 14 and interposed between the inner end of the plunger 17 and the applied plug 16.

25 Secured to the wall W is an elongated hollow member or box B substantially square in cross section and having its opposite ends open. This member or box B is secured to the wall W at a predetermined position below the horizontal plane of the plate 2 and substantially perpendicular to the vertical. The member or box B has secured, as at 20, to a side wall thereof adjacent its opposite ends the cross cleats 21 extending above and below the member or box to provide lugs or feet 22 whereby the member or box may be secured to the wall W by the screws 23 or the like.

The top wall 24 of the member or box B is provided substantially entirely therealong with a slot 25 open at the outer end of the member or box B, the side walls of said slot 25 at the outer or open end portion thereof, as at 26, being disposed in divergence for a purpose to be hereinafter more particularly referred to.

50 The bottom wall 27 of the member or box B directly below the slot 25 is provided with a series of longitudinally spaced openings 28 through which is adapted to be disposed selectively the depending arm 29 arranged at the outer end portion of the rod 11 whereby the door D may be held partly open or ajar as desired.

55 The arm 29 inwardly of its outer or free end is provided with an outstanding annular flange 30 of a maximum diameter in excess of the width of the slot 25 but readily passing between the diverging edges 26 of the slot 25 when the door D is completely closed, said arm 11 being of such a length as to permit the arm 29 to be positioned directly above the space between the diverging edges 26 when the door is in such completely closed position. When in such position the

spring pressed plunger 17 maintains the free end of the arm 29 in contact with the bottom wall 27 of the member or box B with the flange 30 below the top wall 24.

Upon opening movement of the door D 70 the arm 29 will move inwardly of the bottom wall 27 and be caused to drop through the required opening 28 to hold the door ajar or partly open as desired. As the flange 30 is of a maximum diameter greater 75 than the width of the slot 25, it will be understood that the rod 11 together with its arm 29 will operate effectively to prevent anyone outside of the room to completely 80 disengage the arm 29 from the member or box B in order to effect an entrance within the room because the arm 29 can only be freed from the member or box B when the door D is completely closed. Such partly open or ajar position of the door D is indicated by broken lines in Figure 2.

When the door is in its fully open position as indicated by broken lines in Figures 1 and 2 the rod 11 may be thrown back to permit the arm 29 to engage with a suitably 90 positioned keeper 31.

When the device is not in use to hold or check a door ajar or fully open the rod 11 may be swung backward and engaged with the supporting hook 32 or the like carried 95 by the door D so that said rod 11 will be prevented from swinging down and in the way of closing the door.

As disclosed in the accompanying drawings, my improved holder is shown for use 100 at the left side of a door but the same parts can be readily used at the right side of the door it only being necessary to invert the rod 11.

The outer end portion of the top wall 24 105 of the member or box B is provided with the upstanding lugs 33 arranged at opposite sides of the slot 25 and also with the upstanding lugs 34 arranged at opposite sides of the slot 25 and at a point substantially 110 midway of the member or box B.

A person leaving the room and not desiring to completely close the door D and locking it will have a tendency to place the arm 29 inwardly of the outer end of the member or box B with the flange 30 resting on the top wall 24. The lugs 33 and 34 provide stops whereby the door D will be prevented from being blown completely closed or pulled into closed position by someone passing the room. Otherwise upon complete closing of the door D the flange 30 would drop between the incline edges 26 and it would therefore be extremely difficult to again have access within the room. The spring pressed plunger 17 also serves to assure the device to operate in a noiseless manner and which is further facilitated by having the portion of the arm 29 outwardly of the flange 30 tapered so that no lost motion 125 130

is encountered in inserting the arm through an opening 28.

The practicability of the device is further increased by having the plunger 17 in direct contact with the washer 6 which is loose on the bolt or pindle 7 and not in engagement with a rigid knuckle 4.

With the door held ajar by the rod 11, the same can be readily returned to closed position by imposing the requisite lifting or upward swinging movement to the rod 11.

From the foregoing description it is thought to be obvious that a door holder constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a wall having an opening, a swinging closure member therefor, a hollow member secured to the wall adjacent to the opening and provided with a slot in one of its walls, one end of the slot being open, a rod, means for operatively connecting the rod to the door, an arm carried by the rod and insertable with the member through the slot, an enlargement carried by the arm adapted to extend within the member, said enlargement being of a width greater than the width of the slot, the open end portion of the slot being enlarged to permit said enlargement of the arm to pass therethrough, said arm being in position to be moved through the enlarged portion of the slot only when the door is in completely closed position, said member being provided with means for coaction with the arm to hold the door ajar.

2. In combination with a wall having an opening, a swinging closure member therefor, a hollow member secured to the wall adjacent to the opening and provided with a slot in one of its walls, one end of the slot being open, a rod, means for operatively connecting the rod to the door, an arm carried by the rod and insertable with the member through the slot, an enlargement carried by the arm adapted to extend within the member, said enlargement being of a width greater than the width of the slot, the open end portion of the slot being enlarged to permit said enlargement of the arm to pass therethrough, said arm being in position to be moved through the enlarged portion of the slot only when the door is in completely closed position, said member being provided

with means for coaction with the arm to hold the door ajar, the operative connection of the arm to the door permitting the arm to have swinging movement, and means for constantly urging the arm in one direction. 70

3. The combination with a wall having an opening and a swinging closure member for such opening; of a member secured to the wall adjacent to the opening, a plate, means for connecting the plate to the door 75 for movement about an axis parallel to the swinging axis of the door, a rod, means for pivotally connecting the rod to the plate for swinging movement about an axis substantially perpendicular to the axis of the plate, 80 said rod being adapted for sliding engagement with the closure member carried by the wall, coacting means carried by the rod and door for constantly urging the rod toward the member carried by the wall, and coacting means carried by said last named member and rod for locking the rod to the member to hold the closure member against movement when in a partly open position. 85

4. In combination with a wall having an opening, a swinging closure member therefor, a hollow member secured to the wall adjacent to the opening and provided with a slot in one of its walls, one end of the slot being open, a rod, means for operatively 90 connecting the rod to the door, an arm carried by the rod and insertable with the member through the slot, an enlargement carried by the arm adapted to extend within the member, said enlargement being of a width 95 greater than the width of the slot, the open end portion of the slot being enlarged to permit said enlargement of the arm to pass therethrough, said arm being in position to be moved through the enlarged portion of the slot only when the door is in completely 100 closed position, said member being provided with means for coaction with the arm to hold the door ajar, and means for limiting the movement of the rod along the member secured to the wall when the enlargement of the arm is rested upon the exterior surface 105 of said member. 110

5. In combination with a wall having an opening, a swinging closure member therefor, a hollow member secured to the wall adjacent to the opening and provided with a slot in one of its walls, one end of the slot being open, a rod, means for operatively 115 connecting the rod to the door, an arm carried by the rod and insertable with the member through the slot, an enlargement carried by the arm adapted to extend within the member, said enlargement being of a width greater than the width of the slot, the open end portion of the slot being enlarged to permit said enlargement of the arm to pass therethrough, said arm being in position to be moved through the enlarged portion of the slot only when the door is in 120 125 130

completely closed position, said member being provided with means for coaction with the arm to hold the door ajar, and outstanding lugs carried by the wall of the second member provided with the slot and with which the enlargement of the arm of the rod is adapted to contact upon inward swinging

movement of the closure member when said enlargement is rested upon the exterior face of said wall.

In testimony whereof I hereunto affix my signature.

SAMUEL J. RAWLINGS.
